US00D951204S

(12) **United States Design Patent** (10) **Patent No.:** **US D951,204 S**
(45) **Date of Patent:** **** May 10, 2022**

(54) **CONNECTOR**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/804,822**

(22) Filed: **Aug. 23, 2021**

Related U.S. Application Data

(63) Continuation of application No. 29/688,476, filed on Apr. 22, 2019, now Pat. No. Des. 928,716, which is

(57) **CLAIM**

The ornamental design for a connector, as shown and described.

DESCRIPTION

FIG. 1 is a top front perspective view of a connector showing the claimed design;

FIG. 2 is a bottom rear perspective view thereof;

FIG. 3 is a top view thereof;

FIG. 4 is a bottom view thereof;

FIG. 5 is a side view thereof;

FIG. 6 is another side view thereof;

FIG. 7 is a front view thereof; and,

FIG. 8 is a rear view thereof.

The broken lines in the figures show portions of the connector that form no part of the claimed design.

The shade lines in the figures show contour and not surface ornamentation.

1 Claim, 1 Drawing Sheet

Related U.S. Application Data

a continuation of application No. 29/641,690, filed on Mar. 23, 2018, now Pat. No. Des. 846,502, which is a continuation of application No. 29/563,898, filed on May 9, 2016, now Pat. No. Des. 813,820, which is a continuation of application No. 29/502,958, filed on Sep. 22, 2014, now Pat. No. Des. 755,724, which is a continuation of application No. 29/485,445, filed on Mar. 19, 2014, now Pat. No. Des. 713,796, which is a continuation of application No. 29/455,174, filed on May 17, 2013, now Pat. No. Des. 705,176, which is a continuation of application No. 29/426,587, filed on Jul. 6, 2012, now Pat. No. Des. 684,539.
